UNITED STATES PATENT OFFICE.

CAROLINE EBERT AND HENRIETTA C. SHAW, OF KANSAS CITY, MISSOURI.

DESIGN FOR A HAT-FASTENER.

SPECIFICATION forming part of Design No. 30,462, dated April 4, 1899.

Application filed March 10, 1899. Serial No. 708,805. Term of patent 7 years.

To all whom it may concern:

Be it known that we, CAROLINE EBERT and HENRIETTA C. SHAW, of Kansas City, Jackson county, Missouri, have invented and produced 5 a new and original Design for Hat-Fasteners, of which the following is a full, clear, and exact description, reference being had to the accompanying drawings, forming part thereof.

Our invention relates to new and useful de- 10 signs for hat-fasteners.

In the accompanying drawings, Figure 1 is a face view, and Fig. 2 a side view, of a hat-fastener, showing our new design, and the leading or material feature of the same resides 15 in the arch broken at its middle, the broken portion of the arch being bridged or surmounted by a loop, and the rounded loops at the opposite ends of the arch.

Minor features of our design are embraced 20 in the bifurcated form of the arch, so as to provide duplicate arms or parts, in the disposal of said arch-arms some little distance apart, and in the crown-like formation of the bridge-loop, said bridge-loop being also in du- 25 plicate, one bridging the break of each arch-arm. Embraced also in said minor features

are the cross-bars between the arch-arms, said cross-bars bearing circular figures at their ends.

Referring to the drawings in detail, 1 designates the arch.

2 designates the bifurcation thereof.

3 designates the broken part of the arms of the bifurcated arch.

4 designates the crown-like loops bridging 35 the broken arch.

5 designates the rounded loops at the ends of the arch.

6 designates the cross-bars between the arch-arms, and 7 the circular figures on the 40 ends of said bars.

What we claim is—

The design for a hat-fastener, substantially as herein shown and described.

In testimony whereof we affix our signatures in the presence of two witnesses.

CAROLINE EBERT.
HENRIETTA C. SHAW.
